UNITED STATES PATENT OFFICE.

FRANK E. WELLMAN, OF KANSAS CITY, KANSAS, ASSIGNOR TO THE KANSAS CITY GASOLINE COMPANY, OF KANSAS CITY, KANSAS, A CORPORATION OF KANSAS.

SYSTEM FOR CRACKING MINERAL OIL.

1,335,769.

Specification of Letters Patent.

Patented Apr. 6, 1920.

Application filed October 7, 1916. Serial No. 124,327.

To all whom it may concern:

Be it known that I, FRANK E. WELLMAN, a citizen of the United States, residing at Kansas City, county of Wyandotte, State of 5 Kansas, have invented certain new and useful Improvements in Systems for Cracking Mineral Oil, of which the following is a specification, reference being had thereto to the accompanying drawing.

10 My invention relates to the treatment of hydrocarbon oils and has for its object the improvement of apparatus used for that purpose.

15 It is common in systems for cracking hydrocarbons to employ a pipe still or retort heated in a furnace to temperatures up to 900 degrees F., and capable of retaining pressures of 600 pounds and upward. Such stills are liable to damage and destruction 20 in case any portion of the structure should yield or leak. Such damage is often caused by the uneven expansion of the coil due to the heating of the coil in spots much higher than is intended when the heat is unevenly 25 applied.

According to the present invention, I employ the same general type of pipe still or retort referred to, but instead of heating it by means of a furnace, I inject with the oil 30 highly superheated steam which is sufficient to maintain a cracking temperature within the coil and also inject superheated steam from the same source within a jacket of suitable insulating material which surrounds 35 the coil. Thus the temperature is easily-controlled and uniform throughout the still or retort. The pressure is also controlled by regulating the supply of steam and by forcing the oil into the injector and coil by suitable means such as a pump.

40 My invention is illustrated in the accompanying drawings in which:

Figure 1 is a conventional diagram showing the system as a whole.

45 Fig. 2 is a sectional view of the spray nozzle.

Referring to the drawings, A is a steam boiler fitted with superheating coil B. C and G are steam pipes. D is a hand controlled valve. F is a separately fired superheater. H is a cracking coil. L is an oil supply tank. K is a pump. J is a pre-heating coil. I is an oil pipe. M is another

oil pipe leading to a precooler T. N is a spray nozzle. O is a steam pipe containing valve ⁵⁵ o.

The method of operation is as follows:

Steam is generated in the boiler A and partially superheated by the action of the stack gases in the coil B. The steam then 60 passes through the pipe C and the control valve D to the superheater F. It then passes through the pipe G and is discharged into the cracking coil H through the nozzle N, and into the space within the jacket H' 65 through pipe O. The steam pressure is regulated by the hand operated valve D.

The oil to be treated is drawn by the pump K from the tank L or some other suitable receptacle, forced through the heating coil 70 J and discharged in a fine spray into the cracking coil H through the nozzle N. Here the subdivided oil is cracked in contact with the highly superheated steam and the products pass through the pipe M through the 75 precooler T to any suitable cooling system.

The oil and steam are injected into the cracking coil through the spray nozzle N. This nozzle consists of a jacket P into which the steam is admitted through the connection Q. The oil enters through the pipe R. The oil and steam are mixed and given a whirling motion through inclined openings in the tip of the nozzle S at the point where they enter the coil. ⁸⁵

The cracking coil H is preferably made up of straight pipe sections each having an internal diameter of approximately four inches, connected at alternate ends by the welded pipes h, and inclosed within a jacket 90 H' of suitable insulating material to prevent the loss of heat.

Having thus described my invention what I claim and desire to secure by Letters Patent is:

An apparatus for treating hydrocarbon oil consisting of a cracking coil in a steam jacket insulated to prevent loss of heat, means for feeding preheated oil into said cracking coil, means to simultaneously feed 100 superheated steam in a whirling spray into the oil in said coil, and to also simultaneously feed superheated steam from the same source into the steam jacket around the coil.

In testimony whereof I affix my signature, ¹⁰⁵
FRANK E. WELLMAN.
